[57] CLAIM

The ornamental design for a mounting clamp, as shown and described.

DESCRIPTION

FIG. 1 is a perspective view of the mounting clamp;
FIG. 2 is a right side view of the mounting clamp shown in FIG. 1;

FIG. 3 is a top end view of the mounting clamp shown in FIG. 1;

FIG. 4 is a side view of the mounting clamp showing the side opposite that shown in FIG. 2;

FIG. 5 is a bottom view of mounting clamp shown in FIG. 1;

FIG. 6 is a left end view of the mounting clamp shown in FIG. 1; and,

FIG. 7 is a right end view of the mounting clamp shown in FIG. 4.

The broken line showing is for illustrative purposes only and forms no part of the claimed design.
